UNITED STATES PATENT OFFICE.

CHARLES STOLLEBERG, OF TOLEDO, OHIO, ASSIGNOR TO AMERICAN CAN COMPANY, OF JERSEY CITY, NEW JERSEY, A CORPORATION OF NEW JERSEY.

SHEET-METAL CABINET.

SPECIFICATION forming part of Letters Patent No. 723,940, dated March 31, 1903.

Application filed September 4, 1902. Serial No. 122,045. (No model.)

To all whom it may concern:

Be it known that I, CHARLES STOLLEBERG, a citizen of the United States, residing at Toledo, in the county of Lucas and State of Ohio, 5 have invented a new and useful Improvement in Sheet-Metal Cabinets, of which the following is a specification.

My invention relates to improvements in sheet-metal cabinets for holding and delivering cartons, boxes, cans, or packages.

The object of my invention is to provide a cabinet of a simple, efficient, and durable construction, of a neat appearance, and capable of being finely decorated, which will 15 be attractive and ornamental and which will serve for conveniently holding, handling, or delivering cartons, boxes, cans, or packages.

My invention consists in the novel construction of parts and devices and in the 20 novel combinations of parts and devices herein shown or described and by which this object or result is accomplished.

In the accompanying drawings, forming a part of this specification, Figure 1 is a side 25 elevation of a sheet-metal carton-cabinet embodying my invention. Fig. 2 is a vertical cross-section. Fig. 3 is a partial horizontal section on line 3 3 of Fig. 1. Fig. 4 is an enlarged detail horizontal section showing the 30 construction of the partitions.

In said drawings, A represents the non-rotating base of the cabinet, the same being made, preferably, from a single piece of sheet metal stamped up into inverted-dish shape 35 and having a horizontal flange a.

B is the rotating base of the cabinet, the same being preferably of wood and connected to the non-rotating base A by a pivot or bolt b, so that the cabinet may be turned into any 40 position desired on its non-rotating base.

B' is the bottom plate of the cabinet, the same being of sheet metal and having a curved flange b' and a straight or upright flange b'', the latter embracing and covering the edges 45 of the wood rotating base B.

D is the vertical longitudinal center plate of the cabinet, which separates the two series of upright compartments C C' from each other and which is provided at its ends with right- 50 angle flanges d d', uniting it to the sheet-

metal vertical end plates D' D' of the cabinet, the same being preferably soldered thereto. The longitudinal center plate D also has a flange d² at its lower edge for firmly securing it, preferably by solder, to the sheet-metal 55 bottom plate B'.

The vertical end plates D' D' of the cabinet are each provided at each edge with cylindrical rolls d³, forming upright columns, preferably about a half-inch in diameter, at the 60 four corners of the cabinet, which serve to give strength and rigidity to the cabinet as a whole and to the sheet-metal end plates and also a neat and ornamental appearance.

The partitions F between the vertical or 65 upright compartments C C and C' C' are preferably hollow or double, consisting each, preferably, of two partition-plates f f', each having flanges f² at its upright edges for uniting the same to each other and to the longitudinal center plate D and the partition column-plates G. The partition column-plates G each has a pair of cylindrical rolls or columns g g, and being securely fixed or soldered to the hollow or double partitions F 70 serve to give great firmness, strength, and rigidity to the partitions and to the cabinet structure as a whole. The rolls or columns g g are preferably cylindrical or substantially cylindrical in form, and in connection with the corresponding rolls or columns d³ on the end plates D' form vertical guides 75 for holding the cartons, boxes, cans, or packages in the compartments C C', while at the same time exposing them to view. 80

The double or hollow partitions F F are provided with notches or cut-away portions F' at their outer lower corners, the notches being in vertical height somewhat in excess of the thickness of the carton or package to be 85 contained in the compartments, so that the lower carton or package may be slipped out from its compartment while the cartons, boxes, or packages above the lowermost one are held in place by the columns or guides 90 g g d³. The horizontal depth of the notches F' should be sufficient to give room for the finger and thumb to grasp the front end of the carton, box, can, or package X in the compartment. As the partitions F are double or 95 100

hollow, the stacks or piles of cartons or packages in the compartments are thus sufficiently separated from each other to enable the lowermost carton or package to be grasped by 5 the finger and thumb, although the adjacent compartments on either side may be filled with cartons or packages. This hollow, double, or thick construction of the cross-partitions F thus renders it unnecessary to provide the cabinet with any device for pulling or pushing the lowermost carton out or partially out of its compartment, and thus materially simplifies the construction of the cabinet, while at the same time adding to its neatness of appearance and preserving its full efficiency and convenience of operation.

H is the top of the cabinet, the same being preferably of sheet metal and surrounding and embracing the end plates D' and the roll 20 or column plates G, to all of which the top piece is preferably secured by solder. The top piece H has a roll h at its lower edge to strengthen and stiffen the same and give an ornamental finish and appearance to itself 25 and to the cabinet as a whole and an outwardly-flaring part h', which terminates in an upright flange h², having a downward fold h³ at its upper edge, all of which also serves to stiffen and strengthen the top piece and give 30 rigidity and firmness to the cabinet as a whole, while also producing a neat and ornamental appearance. The top piece H is also provided at the lower edge of the upright flange h² with shelves or shoulders h⁴, preferably 35 formed of bent pieces of sheet metal and soldered to the top piece to receive and support the lid K of the cabinet, the shelves or shoulders being preferably located at the corners of the top piece and also, if desired, along its longitudinal sides. The lid K rests on the shoulders h⁴ within the flange h² of the top piece and is provided with downturned flanges K' at its marginal edges, which serve to stiffen the same, and also with an upright longitudinal plate K², which serves as a handle for 45 lifting the lid and also to give an ornamental finish to the cabinet and serve as a sign-plate for the name of the party producing or dealing in goods contained in the cabinet.

50 As my improved cabinet is or may be made as to all its exterior portions and longitudinal and cross-partitions of sheet metal and preferably of tin-plate, it is adapted to receive a fine decoration like other decorative 55 tinware and is at the same time very durable and easily kept in repair and in a perfectly clean and neat appearance. As my cabinet is rotatable upon a non-rotatable base, it may be readily turned into any position on a 60 counter or other stand, where it may be placed as may be desired or required from time to time for delivering or exposing to view the cartons or packages in any of the compartments on either of the two fronts of 65 the cabinet. As my cabinet contains two sets or series of vertical compartments arranged back to back, the cabinet having a double

front or two fronts, the same may be made very compact and substantial, while at the same time containing a large number of compartments.

The top piece H at its upright portion h⁵ affords means for placing thereon over each compartment the name of the article contained in the cartons, boxes, cans, or packages placed in each compartment—as, for example, "Pepper," "Cinnamon," "Cloves," "Allspice," "Ginger," "Mustard."

I claim—

1. A sheet-metal cabinet for holding and delivering cartons, boxes, cans or other packages and comprising in combination a non-rotatable base A, a rotatable base-piece B, a bottom plate B' secured thereto, vertical longitudinal center plate D, end plates D' D' 85 having cylindrical rolls or columns d³ at their vertical edges, double or hollow cross-partitions F, roll or column-plates G having cylindrical rolls or columns g at their edges serving as guides to hold the cartons or packages in place and provided with notches F' at their lower front corners, top piece H having roll h at its lower edge, flaring portion h' and upright flange h² and lid K having a handle and sign-plate K², said cabinet having 90 two sets or series of upright compartments C and C' separated by said longitudinal plate, D, substantially as specified.

2. A sheet-metal cabinet comprising in combination a base-plate B', longitudinal plate D, 100 end plates D' D', and a series of double or hollow cross-partitions F having notches F' at their lower outer corners to enable the lowermost carton or package to be conveniently grasped by the fingers and pulled out, substantially as specified.

3. A sheet-metal cabinet comprising in combination a base-plate B', longitudinal center plate D, end plates D' D', and a series of double or hollow cross-partitions F having notches 110 F' at their lower outer corners to enable the lowermost carton or package to be conveniently grasped by the fingers and pulled out, said cabinet having two sets or series of compartments C C' separated by said longitudinal 115 center plate, substantially as specified.

4. A sheet-metal cabinet comprising in combination a base-plate B', longitudinal center plate D, end plates D' D', and a series of double or hollow cross-partitions F having notches 120 F' at their lower outer corners to enable the lowermost carton or package to be conveniently grasped by the fingers and pulled out, and column-plates G having columns g g serving as guides to retain the cartons or packages in the compartments of the cabinet while permitting the lowermost carton or package to be pulled out, substantially as specified.

5. A sheet-metal cabinet comprising in combination a base-plate B', longitudinal center 130 plate D, end plates D' D', and a series of double or hollow cross-partitions F having notches F' at their lower outer corners to enable the lowermost carton or package to be conven-

- fently grasped by the fingers and pulled out, and column-plates G having columns $g\ g$ serving as guides to retain the cartons or packages in the compartments of the cabinet while 5 permitting the lowermost carton or package to be pulled out, said cabinet having two sets or series of compartments C C' separated by said longitudinal center plate, substantially as specified.
- 10 6. A sheet-metal cabinet comprising in combination a bottom plate B', longitudinal center plate D, end plates D' D' having columns d^3 , partitions F having notches F' at their lower outer corners, and column-plates G 15 having columns $g\ g$, substantially as specified.
7. A sheet-metal cabinet comprising in combination a bottom plate B', longitudinal center plate D, end plates D' D' having columns d^3 , partitions F having notches F' at their lower outer corners, column-plates G having columns $g\ g$ and top piece H surrounding and embracing said end plates D' and column-plates G, substantially as specified.
- 20 8. A sheet-metal cabinet comprising in combination a bottom plate B', longitudinal center plate D, end plates D' D' having columns d^3 , partitions F having notches F' at their lower outer corners, column-plates G having 25 columns $g\ g$ and top piece H surrounding and embracing said end plates D' and column-plates G, said top piece H having a roll h at its lower edge and an upright flange h^2 to receive the lid, and a lid K, substantially as specified.
- 30 9. A sheet-metal cabinet comprising in combination a bottom plate B', longitudinal center plate D, end plates D' D' having columns d^3 , partitions F having notches F' at their lower outer corners, column-plates G having columns $g\ g$ and top piece H surrounding and embracing said end plates D' and column-plates G', said top piece H having a roll h at its lower edge and an upright flange h^2 to receive the lid, and a lid K, said lid K having a handle and sign-plate K², substantially as specified.
- 35 10. A sheet-metal cabinet comprising in combination a bottom plate B', longitudinal center plate D, end plates D' having notches D^2 at their outer lower corners and guide-columns d^3 at their edges, double cross-partitions F having notches F' at their outer lower corners and guide-columns $g\ g$ at the outer edges of said cross-partitions F, substantially as specified.
- 40 11. A sheet-metal cabinet comprising in combination a bottom plate B', longitudinal center plate D, end plates D' having notches D^2 at their outer lower corners and guide-columns d^3 at their edges, double cross-partitions F having notches F' at their outer lower corners, and guide-columns $g\ g$ at the outer edges of said cross-partitions F, a top 45 piece H surrounding and embracing the end plates D' D' and cross-partitions F and guide-columns g , substantially as specified.
12. A sheet-metal cabinet comprising in combination a bottom plate B', longitudinal center plate D, end plates D' having notches D^2 at their outer lower corners and guide-columns d^3 at their edges, double cross-partitions F having notches F' at their outer lower corners and guide-columns $g\ g$ at the outer edges of said cross-partitions F, a top 50 piece H surrounding and embracing the end plates D' D' and cross-partitions F and guide-columns g , and lid K, substantially as specified.
13. A sheet-metal cabinet comprising in combination a bottom plate B', longitudinal center plate D, end plates D' having notches D^2 at their outer lower corners and guide-columns d^3 at their edges, double cross-partitions F having notches F' at their outer lower corners and guide-columns $g\ g$ at the outer edges of said cross-partitions F, a top 55 piece H surrounding and embracing the end plates D' and cross-partitions F and guide-columns g , and lid K, said cabinet having two sets or series of vertical compartments C C' separated by said longitudinal center plate D, substantially as specified.
14. A sheet-metal carton-cabinet comprising in combination a bottom plate, a vertical longitudinal plate, a pair of end plates, a series of double or hollow cross-partitions dividing the cabinet into a series of upright compartments, and a series of column-strips secured to the front or outer upright edges of the cross-partitions, substantially as specified.
15. A sheet-metal carton-cabinet comprising in combination a bottom plate, a vertical longitudinal plate, a pair of end plates, a series of double or hollow cross-partitions dividing the cabinet into a series of upright compartments, and a series of column-strips secured to the front or outer upright edges of the cross-partitions, said end plates having integral columns or guides at their front or outer edges, substantially as specified.
16. A sheet-metal carton-cabinet having a bottom plate, a vertical longitudinal center plate, a pair of end plates and a series of cross-partitions on each side of the longitudinal center plate dividing the cabinet into two series or sets of upright partitions, said end plates and cross-partitions having hollow guide-columns at their front or outer edges, one pair for each compartment, said hollow guide-columns serving to stiffen and strengthen the cabinet and being notched or cut away at the bottom of the case to permit the withdrawal of the lowermost cartons or packages while holding those above in place, substantially as specified.
17. A sheet-metal carton-cabinet having a bottom plate, a vertical longitudinal center plate, a pair of end plates and a series of cross-partitions on each side of the longitudinal center plate dividing the cabinet into two series or sets of upright partitions, said end plates and cross-partitions having guide-columns at their front or outer edges, one pair

for each compartment, said end plates and cross-partitions being provided with notches at their lower outer corners to enable the lowermost carton to be grasped and pulled out, substantially as specified.

18. A sheet-metal carton-cabinet having a bottom plate, a vertical longitudinal center plate, a pair of end plates and a series of cross-partitions on each side of the longitudinal center plate dividing the cabinet into two series or sets of upright partitions, said end plates and cross-partitions having guide-columns at their front or outer edges, one pair

for each compartment, said end plates and cross-partitions being provided with notches at their lower outer corners to enable the lowermost carton to be grasped and pulled out, and a sheet-metal top piece surrounding and embracing the end plates and cross-partitions and the columns or guides thereon, substantially as specified. 15 20

CHARLES STOLLBERG.
